Primary Examiner — Paula Allen Greene*(74) Attorney, Agent, or Firm* — Justin Lampel(57) **CLAIM**

The ornamental design for a microphone, as shown and described.

DESCRIPTION

FIG. 1 is a front, right, and top perspective view of a microphone, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1 comprising an adjusting knob.

The broken lines shown in the drawings are included for the purpose of illustrating portions of the microphone that form no part of the claimed design.

The dot-dash broken lines encircling portions of the microphone in FIG. 1 and illustrated in the enlarged view of FIG. 9 form no part of the claimed design.
